UNITED STATES PATENT OFFICE.

ALFRED M. HEWLETT, OF KEWANEE, ILLINOIS.

APPARATUS FOR MANUFACTURING PIPE.

SPECIFICATION forming part of Letters Patent No. 537,453, dated April 16, 1895.

Application filed April 24, 1894. Serial No. 508,888. (No model.)

To all whom it may concern:

Be it known that I, ALFRED M. HEWLETT, a citizen of the United States, residing at Kewanee, in the county of Henry and State of

Illinois, have invented certain new and useful Improvements in Apparatus for Manufacturing Pipe, of which the following is a specification, reference being had to the accompanying drawings, in which—

10 Figure 1 is a plan view. Fig. 2 is a side elevation, part of the bell holder being in section; and Fig. 3 is an end elevation of the bell holder support.

15 My invention relates to the manufacture of butt-weld pipe by drawing a skelp through a bell, and has particularly to do with mechanism for supporting the bell or bells through which the skelp is drawn.

20 Heretofore it has been customary to draw the skelp through a bell supported upon a draw bench, the draw bench having an endless chain to which the tag was adapted to be connected. As it is necessary in order to economize time that several strips or pieces of skelp 25 should be placed in the furnace side by side, in order to avoid the necessity of changing the position of the skelps in the furnace it has been attempted to make the draw bench movable laterally in front of the furnace so 30 that the bell could be moved opposite the different skelps, as it is necessary to do to make good pipe.

25 In my application of even date herewith I have shown improved apparatus for manufacturing pipe by which the objections incident to the use of the old laterally-movable draw bench are avoided, such construction consisting essentially in a series of bell holders arranged in front of the furnace, such 40 bell holders being detached from the drawing mechanism, which consists of a draw bar provided with suitable mechanism for reciprocating it. For certain purposes, however, it is desirable that the bell should be held 45 slightly above the lower edge of the furnace when drawing the pipe, but when the bell holders are arranged to hold the bells in such position the furnace cannot be readily charged. In my improved apparatus, however, I have devised means whereby the bell 50 holders may be moved away from in front of the furnace door when the furnace is to be

charged, thereby avoiding the above objection, and this, broadly stated, is the principal feature of the invention which forms the subject matter of this application. 55

My invention further consists in the provision of means for automatically operating the bell holders.

That which I regard as new will be set forth 60 in the claims.

In the drawings,—4 indicates a furnace, of which 5 is the door.

6 indicates the drawing mechanism, which may be of any approved form. I prefer, 65 however, to use the form shown in my application above referred to, in which a laterally-movable draw bar 7 is connected to a bar 8, which bar is connected to a piston rod 9 working in a steam cylinder 10. A hand lever 11 is provided for controlling the admission of steam to the cylinder 10 so that the piston rod 9 may be reciprocated toward and from the furnace for drawing the pipe. As the drawing mechanism is fully described in 70 my said application I do not consider it necessary to describe it in detail herein. 75

12 indicates a bell-holder support, which is located in front of and at such a distance from the furnace that the bells will be supported at the proper distance from the furnace. The bell-holder support 12 is provided at each end with standards 13—14. Between each pair of such standards is mounted a sliding block 15, the standards 13—14 serving 80 as guides for the blocks 15, so that said blocks are vertically movable between said standards. Connecting the two blocks 15 is a box 16, which is adapted to carry bell holders 17, which are preferably of the form shown in 85 my application hereinbefore referred to, the box 16 being curved so that the bell holders will be arranged in the arc of a circle. 90

18 indicates bells, which are adapted to be carried by the bell holders. 95

19 indicates a shaft, which is supported by the bell-holder support 12, and extends longitudinally of the same.

20 indicates links, one of which is fixedly connected to the shaft 19 near each end 100 thereof, which links are pivotally connected to links 21, the latter links being connected also to the blocks 15, thereby forming a toggle joint at each end of the bell-holder sup-

port. The length of the links 20-21 is such that when they are in line with each other the bell-holders will be in such position as to hold the bell at the proper height, whereas, by moving said links out of line, the bell-holders may be lowered sufficiently to permit of ready access to the furnace.

In order to operate the bell holders automatically I provide a lever 22, which is pivoted upon the bar 8, and carries at its free end a hook 23 adapted to engage the upper end of a cross head 24 carried by the shaft 19, as best shown in Fig. 2, the end of said lever being beveled so that it will be lifted 15 automatically to permit the hook to catch said cross head when the bar 8 is moved toward the furnace. When the bar 8 moves away from the furnace, as in drawing a pipe, by means of the lever 22 the upper portion 20 of the cross head 24 will be drawn in the same direction, thereby rocking the shaft 19 and lifting the bell holders through the toggle links 20-21. When the bar 8 is moved a short distance the hook 23 will be moved out 25 of engagement with the cross head 24 by a stationary cam 25 which is in position to engage an inclined portion 26 of the lever 22, the end of the lever 22 thereby being raised sufficiently to release the cross head 24. The 30 releasing mechanism is so adjusted as to cause the lever 22 to release the cross head 24 when the links 20-21 come into line with each other, and thereby lock the bell holders in their uppermost position. The bell holders 35 are automatically returned to their lowermost position when the pipe has been drawn through the bell by means of an arm 27 carried by the bar 8, which arm is adapted to strike the hooked end of a rod 28 which is connected 40 to the lower end of the cross head 24, thereby moving such rod sufficiently to rock the shaft 19 and cause the bell holders to descend. It will be seen that by this construction the bell 45 holders are moved into position to support the bells when the pipe is to be drawn, and after the operation of drawing is completed are immediately moved away from the door of the furnace, so that the furnace may be charged without inconvenience.

50 As it is evident that the bell-holding devices are not dependent upon any particular drawing mechanism, I do not wish to limit myself to the use of such devices in connection with drawing mechanism of any particular form, except that, as far as the specific mechanism for automatically operating the bell holders is concerned, it can be used only with reciprocating drawing mechanism.

That which I claim as my invention, and 60 desire to secure by Letters Patent, is—

1. The combination with the pipe-drawing mechanism, of bell-holding devices, mounted independent of the drawing mechanism and movable away from the furnace door to permit 65 the charging of the furnace, and mechanism for operating said bell-holding devices to

move them into or out of operative position, substantially as described.

2. The combination with transversely movable pipe-drawing mechanism, of a series of 70 detached bell-holders movable independent of the drawing mechanism, and means for moving the bell-holders away from in front of the furnace door to permit the charging of the furnace, substantially as described.

75 3. The combination with pipe - drawing mechanism, of a vertically movable bell-holder supported independent of said pipe-drawing mechanism, and means for moving the bell-holder vertically, substantially as de- 80 scribed.

4. The combination with pipe - drawing mechanism, of a vertically movable bell-holder supported independent of said pipe-drawing mechanism, substantially as de- 85 scribed.

5. The combination with a furnace, and pipe drawing mechanism, of a vertically movable bell-holder located between the pipe-drawing mechanism and the furnace, and means for 90 automatically raising the bell-holder when a skelp or strip is to be drawn, substantially as described.

95 6. The combination with pipe - drawing mechanism, of a vertically movable bell-holder, automatically operating mechanism for moving said bell holder into operative position as the skelp is drawn from the furnace, and means for moving said bell holder out of operative position after the pipe has 100 been formed, substantially as described.

105 7. The combination with supporting devices, of a vertically movable bell holder, and automatically operating mechanism actuating the bell holder to move the bell or bells 110 into position to receive the skelp and away from in front of the furnace door to permit the furnace to be charged, substantially as described.

110 8. The combination with reciprocating pipe-drawing mechanism, of a vertically movable bell holder, and mechanism automatically operated by the drawing mechanism for actuating said bell holder to move the bell or bells 115 into position to receive the skelp and out of the way to permit the furnace to be charged, substantially as described.

120 9. The combination with pipe - drawing mechanism, and a bell-holder support mounted independent of the pipe drawing mechanism, of one or more bell holders vertically movable upon said support, and toggle mechanism for moving said bell holders vertically, substantially as described.

125 10. The combination with a bell-holder support, of sliding blocks 15, a box connected to said blocks and adapted to carry bell holders, a shaft 19, links 20-21 connected to said shaft, and means for rocking said shaft for the purpose of moving said bell holders vertically, 130 substantially as described.

11. The combination with supporting de-

5 vices, and one or more bell holders, of a shaft 19, toggle links 20—21, reciprocating drawing mechanism, and devices operated by the movement of said drawing mechanism to rock said

15 shaft, substantially as described.

by said drawing mechanism, a rod 28 connected to said cross head and adapted to be engaged by said arm, a cam 25, and means for releasing said lever 22 from said cross head 15 after the bell holders have been moved into operative position, substantially as described.

ALFRED M. HEWLETT.

Witnesses:

JOHN L. JACKSON,
ALBERT H. ADAMS.

10 12. The combination with supporting devices, and vertically movable bell holders, of toggle links 20—21, a shaft 19, a cross head 24 carried by said shaft, reciprocating drawing mechanism, a lever 22 carried thereby, said lever having a hook 23, an arm 27 carried
